UNITED STATES PATENT OFFICE.

DOUGLAS BROOKFIELD, OF HOLLOWAY, LONDON, ENGLAND.

SMELTING-FURNACE.

1,346,527.

Specification of Letters Patent. Patented July 13, 1920.

Application filed March 21, 1919. Serial No. 284,195.

To all whom it may concern:

Be it known that I, DOUGLAS BROOKFIELD, a subject of the King of Great Britain, residing at Holloway, London, N. 7, England, 5 have invented new and useful Improvements in Smelting-Furnaces, of which the following is a specification.

This invention relates to improved mechanism for effecting the tilting operation of 10 crucible smelting furnaces, particularly of that class known as the lip-axis type, by the employment of which and the general arrangement thereof increased facility of manipulation is secured, besides the aggregate weight of the apparatus being reduced 15 and the necessity for the use of counterbalance weights avoided. Incidentally by the general arrangement of parts as hereafter described a very compact apparatus is produced by combining on the one bedplate a complete plant comprising the furnace proper, lifting gear for the preheater or closure, tilting gear for the furnace, and motive power for driving alternatively the fan 20 or blower for the blast that is also mounted on the same bedplate, and the said tilting gear.

As an example of the embodiment of my present invention, I will presume its application to a furnace provided with the characteristic features set out in the specification of a co-pending application for patent, Serial No. 208,886, filed December 26, 1917, in the names of James Gaunt and Douglas 35 Brookfield, wherein the air blast is preheated by being conveyed through circuitous conduits disposed in an annular space formed between the inner and outer casing of the furnace preparatory to its admission to the furnace, the said furnace being provided with a preheater or metal container that forms a closure for the top thereof, and means for raising this cover and swinging the same clear of the body of the furnace. 40 Given a furnace of this kind, provided with a spout or pouring lip at or near the top just below the preheater or metal container, supported on trunnions mounted in bosses provided on the outer casing of the furnace 45 50 carried in standard bearings secured to the bedplate of the machine, on one of the said trunnions or axes is mounted a worm-wheel that is rotated by a worm driven by any convenient means, this worm-wheel drives a pinion that meshes with a spur-wheel se-

cured to a spindle, at or near the outer ends of which are fixed pinions that engage with sectoral toothed racks, that cause the said spindle to be moved in an upward direction carrying with it the furnace by reason of its engagement therewith, a boss on the furnace casing being provided therefor, whereby the furnace is caused to tilt on the axis which, as before stated, is situated about the same plane or center line as the lip or spout aforesaid.

In order that my invention may be clearly understood I will now describe the same with reference to the accompanying sheet of drawings, in which:—

Figure 1 is a front elevation, partly in section, of a furnace of the kind referred to adapted to the lip-axis tilting type.

Fig. 2 a side elevation, partly in section.

Fig. 3 a plan of the entire combination. 75

Fig. 4 a part sectional plan taken on line x—x of Fig. 2, showing the tilting gear drawn to a larger scale.

The furnace *a* and preheater *b* mounted thereon together with the preheater lifting gear *c* are of similar construction to that described in the specification of the co-pending application hereinbefore referred to. The furnace *a* is carried by the trunnions *d* mounted in bearings *e* bolted to the main frame *f*. Formed in the casting by which the trunnions *d* are attached to the furnace *a* is the lip *g* by which the contents of the crucible within the furnace are poured, which lip is situated at or near the center line of the axis on which the furnace rotates during the tilting operation. Mounted on the main frame *f* is the casing *h* inclosing the mechanism by which the tilting operation is carried out, and which may consist of the casting *i* to which is bolted the cover-plate *j*. On the side of the casing *i*, and either formed integral therewith or bolted thereto, is the toothed sector *k* into which gears the pinion *m* mounted on the spindle *n*. 100

On the other end of the spindle *n* is mounted a similar pinion *o* that gears with the toothed sector *p* which is bolted or otherwise attached to the cover-plate *j*. The spindle *n* is carried by the bearings or guides *q* working in the slots *r* formed in the casing *i* and cover-plate *j*, and at its inner end takes into the boss *s* formed on the side of the furnace *a*. Mounted on the spindle *n* is a spur-wheel *t* that is driven 105 110

by the pinion u on the spindle v which is carried in bearings formed in the casing i and cover-plate j . Formed integral with the pinion u is the worm-wheel w which is driven by the worm x mounted on the vertical shaft y journaled in the casing i at z . At the lower end of the vertical shaft y is fixed the bevel-wheel 1 which gears with a similar wheel 2 mounted on the driving-shaft 3 , that is carried in bearings 4 formed in the casing i .

Motion is imparted to the driving-shaft 3 by means of the electric motor 8 mounted on the main frame f , through the friction clutch 7 , worm-shaft 6 , and speed-reducing gear 5 which is of the ordinary worm and worm-wheel type. Mounted on the main frame f on the other side of the motor 8 is the blower or fan 10 adapted to be driven through the friction-clutch 9 by the motor 8 . The air blast from the fan or blower 10 is taken into the hollow main frame f to the inlet 11 on the furnace a , the hollow frame f acting as a conduit for said air blast. It will be obvious that when the furnace is being tilted the air blast must be stopped, and to insure this taking place we prefer to arrange that the gear operating the clutches 7 and 9 shall be interconnected in such a manner that both clutches cannot be in engagement at the same time. One method of effecting this is illustrated in Fig. 3 in which the operating bar 12 is connected to the operating levers 13 and 14 in such a manner that when the clutch 9 , for example, is in gear and the fan or blower 10 is being driven by the motor 8 , the clutch 7 for driving the tilting mechanism is out of gear with the motor. When the operating bar 12 is in the intermediate position both clutches will be inoperative and the motor is free, as for example when starting up.

Assuming now that it is required to tilt the furnace for pouring, the operating bar 12 is moved so as to disengage the clutch 9 by means of the lever 14 and put the clutch 7 in gear by means of the lever 13 . The motor 8 thus imparts motion to the tilting gear through worm-shaft 6 , reducing gear 5 , driving-shaft 3 , to the bevel-wheels 2 and 1 by which the vertical shaft y is driven. This in turn drives through worm x , the worm-wheel w and the pinion u , the latter gearing with the spur-wheel t on spindle n and driving the pinions m and o which, engaging with the toothed sectors k and p respectively, cause the spindle n to move in an upward direction carrying with it the furnace a by reason of its engagement with the boss s on the side of the furnace a ,

which is thus caused to tilt on the trunnions d as indicated by dotted lines in Fig. 2, which shows the furnace a in the midway position, the preheater or closure b having been previously removed.

The lowering operation is effected by reversing the direction of rotation of motor 8 .

It will be obvious that any form of power other than the electric motor 8 may be employed, such as a gas or oil engine, or belt pulleys may be fitted by which motion can be taken from a line of shafting, in the latter case the employment of an open or cross belt in conjunction with striking gear, such as is employed in the case of planing machines, fulfills the requirements as to reverse motion of the tilting operation.

Claims:

1. In a smelting furnace of the lip-axis type, the combination with the blowing mechanism of tilting mechanism comprising a set of gear wheels mounted at the axis on which the furnace is tilted, a second set of gear wheels driven thereby, a spindle on which said second set of gear wheels is mounted, said spindle being connected to the furnace at a distance from the tilting axis, a plurality of sectoral racks engaging with said second set of gear wheels, and means for driving the first set of gear wheels.

2. In a smelting furnace of the lip-axis type the combination with a set of gear wheels mounted at the axis on which the furnace is tilted, a second set of gear wheels driven thereby, a spindle on which said second set of gear wheels is mounted, said spindle being connected to the furnace at a distance from the tilting axis, sliding bearings supporting said spindle, a plurality of sectoral racks engaging with said second set of gear wheels, and means for driving the first set of gear wheels, of a blower, and means for driving said blower.

3. In a smelting furnace of the lip-axis type the combination with a set of gear wheels mounted at the axis on which the furnace is tilted, a second set of gear wheels driven thereby, a spindle on which said second set of gear wheels is mounted, said spindle being connected to the furnace at a distance from the tilting axis, sliding bearings supporting said spindle, a plurality of sectoral racks engaging with said second set of gear wheels, and means for driving the first set of gear wheels, of a blower, means for driving said blower, and means for disconnecting said blower driving means when the furnace is being tilted.

In witness whereof I affix my signature.
DOUGLAS BROOKFIELD.
